CLAIM

The ornamental design for a pin as shown and described.

DESCRIPTION

FIG. 1 is a front perspective view of a pin, showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a rear perspective view thereof.

The broken line showing is included for the purpose of illustrating portions of the “article” and forms no part of the claimed design. The dash-dot-dash lines disclose the boundary between the claimed and unclaimed areas of the design.
